Patented May 9, 1922.

UNITED STATES PATENT OFFICE.

WILLIAM G. JENSEN, OF BARTLESVILLE, OKLAHOMA.

PUMP JACK.

1,415,037.

Specification of Letters Patent.

Patented May 9, 1922.

Application filed August 17, 1920. Serial No. 404,230.

To all whom it may concern:

Be it known that I, WILLIAM GUY JENSEN, a citizen of the United States, and a resident of Bartlesville, in the county of Washington and State of Oklahoma, have invented certain new and useful Improvements in Pump Jacks, of which the following is a specification.

The present invention relates to pump jacks.

The object of the invention is to provide a pump jack which is of simple and durable construction, reliable in operation and easy to manufacture and install, which is adapted to the requirements of various characters of wells and which imparts a pure rectilinear motion to the polish rod of the pump so as to operate the rod with the minimum wear on the same and on its stuffing boxes and associated structure.

Other objects and advantages of the invention reside in certain novel features of construction, combination and arrangement of parts as will be hereinafter more fully described and particularly pointed out in the appended claim, reference being had to the accompanying drawings forming part of this specification, and in which,

Figure 1 is a side elevational view of the pump jack, in full lines showing the parts as seen in one position and in dotted lines showing the parts of the same in another position; and

Figure 2 is a detail view of the pivotal connection of the pivoted standard.

Referring to the drawings, it will be seen the invention contemplates a pump jack adapted to be associated with a pump P of any conventional character which has as usual a stuffing box S and a polish rod R. The pump jack as usual imparts a reciprocating movement to the polish rod.

The pump jack includes a suitable base or foundation 10. A transverse sill 11 is suitably secured to the base 10 and carries a stationary frame 12. The stationary frame 12 is provided with an extension in the form of an inclined member 13 secured, as at 14, to the main frame and adjustably secured, as at 15, to a sill 16 arranged upon the base.

A standard 17 is pivotally mounted, as at 18, at its lower end upon the sill 16, so as to be free to partake of a limited degree of swinging motion about the pivot 18. An arm 19 is pivoted at one end, as at 20, to the upper end of the standard 17 and is adapted

to be connected at its other end, as designated at 21, to the polish rod R. A link 22 is pivotally mounted, as at 23, to the outer end of the extension 13 of the stationary frame so that the link is constrained to motion about a fixed pivot. The outer end of the link is pivoted, as at 24, to the arm 19 intermediate the connection 21 of the arm to the polish rod and the pivotal connection 20 of the arm to the upper end of the pivoted standard but nearer to the connection 20.

Means is provided for actuating the arm 19. This means preferably consists of a rocking frame 25 of triangular form fulcrumed on the main frame, as at 26. A pull rod 27 is provided for rocking the frame 25. A connecting rod 28 has its lower end pivotally secured to the rocking frame 25, as at 29, and has its upper end suitably engaged with the arm 19, as at 30, so that motion from the rocking frame is imparted to the arm 19.

In operation as the pull rod 27 is reciprocated it rocks the frame 25 about its pivot 26. The rocking frame 25 through the connecting rod 28 imparts motion to the arm 19. On the upward movement of the connecting rod 28 the arm 19 moves upwardly and about its pivot 20. The end of the arm at the connection 21 thereof to the polish rod however partakes of pure rectilinear motion. This is due to the combined action of the link 22 and the pivoted standard 27. For on the upstroke of the arm 19 the link 22 is constrained to partake of pivotal motion in a direction opposite to that of the pivotal motion of the arm 19 and the standard 17 being free to move is displaced to the extent necessary to compensate for the pivotal motion of the arm 19 so that the end thereof connected to the polish rod moves in a straight line. This action can be readily understood from an inspection of Figure 1 of the drawings in which the parts are shown in initial position in full lines and at the end of the upward stroke in dotted lines. As shown in dotted lines the link 22 has partaken of its motion about its fixed pivot in a direction opposite to that of the arm 19 and has displaced the pivoted standard 17 sufficiently to compensate for the pivotal motion of the arm 19 and permit the outer end thereof to reciprocate rectilinearly.

This arrangement permits the use of available and inexpensive instrumentalities

to impart the correct character and degree of motion to the polish rod so that the life of the polish rod, stuffing boxes and associated elements is much longer and their efficiency 5 is greatly increased.

Having thus described my invention, I claim:

A pump jack comprising a base, a stationary frame arranged upon said base and 10 having an extension, a standard pivoted at its lower end to said base, an arm pivotally secured at one end to the upper end of said standard and adapted to be connected at its

other end with the polish rod of the pump, a link having one end pivotally secured to the frame extension and the other end pivotally secured to the arm whereby the arm at its connection to the polish rod is constrained to rectilinear motion, and means for actuating said arm including a rocking frame carried by the stationary frame and a connecting rod transmitting motion from the rocking frame directly and immediately to the arm. 1

WILLIAM G. JENSEN. 2
